(57) **CLAIM**

The ornamental design for a grill cover, as shown and described.

DESCRIPTION

FIG. 1 is a front, top perspective view of a grill cover, showing my new design;

FIG. 2 is a rear, bottom perspective view thereof;

FIG. 3 is a front elevational view thereof;

FIG. 4 is a rear elevational view thereof;

FIG. 5 is an enlarged left side view thereof;

FIG. 6 is an enlarged right side view thereof;

FIG. 7 is a top plan view thereof;

FIG. 8 is a bottom plan view thereof;

FIG. 9 is an enlarged detail view of portion 9 in FIG. 1;

FIG. 10 is an enlarged detail view of portion 10 in FIG. 1;

FIG. 11 is an enlarged detail view of portion 11 in FIG. 1;

FIG. 12 is an enlarged detail view of portion 12 in FIG. 2;

FIG. 13 is an enlarged detail view of portion 13 in FIG. 2;

FIG. 14 is an enlarged detail view of portion 14 in FIG. 3;

FIG. 15 is an enlarged detail view of portion 15 in FIG. 4;

FIG. 16 is an enlarged detail view of portion 16 in FIG. 5;

FIG. 17 is an enlarged detail view of portion 17 in FIG. 7;

FIG. 18 is an enlarged detail view of portion 18 in FIG. 7;

FIG. 19 is an enlarged detail view of portion 19 in FIG. 8;

and,

FIG. 20 is an enlarged detail view of portion 20 in FIG. 8. The dashed broken lines in the figures are for the purposes of illustrating portions of the grill cover and form no part of the claimed design.

The dash-dot-dash lines illustrate the border of the enlarged details views and form no part of the claimed design.

The area shown between the broken lines and inner solid edge lines do not form part of the claimed design.
